Delaware

Application December 18, 1953, Serial No. 28,127

Term of patent 7 years

(Cl. D48—32)

To all whom it may concern:

Be it known that I, James H. Sipple, a citizen of the United States of America, being a resident of Royal Oak, Michigan, have invented a new, original, and ornamental Design for a Tail Lamp Assembly, of which the following is a specification, reference being made to the accompanying drawing, forming a part thereof.

In the drawing:

Fig. 1 is a side elevational view of a tail lamp assembly embodying my new design;

Fig. 2 is a top plan view; and

Fig. 3 is a rear elevational view thereof.

The fragmentary fender and bumper elements shown in broken lines in Fig. 1 are disclosed only for the purposes of illustration.

I claim:

The ornamental design for the tail lamp assembly, substantially as shown and described.
